Daniel Bull
Improved Table Leaf Supporter

PATENTED

JAN 7 1868

United States Patent Office.

DANIEL BULL, OF AMBOY, ILLINOIS.

Letters Patent No. 72,970, dated January 7, 1868.

IMPROVED TABLE-LEAF SUPPORT.

The Schedule referred to in these Letters Patent and making part of the same.

TO ALL WHOM IT MAY CONCERN:

Be it known that, I, DANIEL BULL, of Amboy, in the county of Lee, and State of Illinois, have invented a new and useful Improved Table-Leaf Supporter; and I do hereby declare and make known that the following is a full, clear, and exact description of the same, reference being had to the accompanying drawings, and the letters and figures marked thereon, which form part of this specification.

My said invention consists in a novel device for supporting the leaves of table, it being constructed and arranged, with respect to the table-leaf and the rail of the table, in such a manner that, upon raising up the leaf, the support sets itself in the proper position to sustain the leaf automatically, while, by a simple and easy adjustment, it can be unset to allow the leaf to fold down as desired.

To enable those skilled in the art to understand how to make, apply, and use my invention, I will now describe the same with particularity, making reference in so doing to the aforesaid drawings, in which—

Figure 1 represents a side view of the same.

Figure 2, a bottom view thereof.

Figure 3, a top view of that part of the device attached to the leaf; and

Figure 4, a longitudinal central section of the same.

Similar letters of reference in the several figures denote the same parts of my invention.

T represents an ordinary table, L the leaf of the same, and R the rail. A represents the brace or supporting-arm, which is constructed in form of a link, as shown in fig. 2, and may be made of wire, of any suitable size, or of other material, as preferred. Said link is secured at one end by means of a clasp, B, to the rail R, so as to have a free motion at that point as upon a hinge, the clasp B being secured to the rail by screws, or their equivalent, marked *bb*. D represents a metallic bar, which is secured to the leaf, as shown by screws C, passing through slots *d* in said bar D, which is formed with a recess upon its upper side, to receive one end of the link A, as shown, which slides along in said recess when the leaf is folded or turned down, and which is prevented from sliding, when the leaf is set, by a bar or stop, E, as is clearly shown in fig. 1. The said bar E is provided with a pin or projection, *m*, which enters a corresponding recess or groove in the bar D, marked *l*, which prevents any longitudinal displacement of said bar E, while its opposite forked end, as seen in fig. 3, at *g*, strides a point or spur, *f*, on the bar D, which prevents any lateral displacement of said bar E. In fig. 1, the red lines show the position of the parts when the leaf is turned down. When the leaf is raised, the end of the link A slides to the end of the recess in the bar D, and lies beneath the spur *f*, passing from beneath the end of the bar E, which then automatically, of its own weight, drops down and locks the link A beneath the spur *f*, which thus prevents the link from passing above the bar E, and so sets the leaf firmly and securely as desired. The forked end of the bar E is made a trifle thicker than the space between the spur *f* and the lower bar D, so that when the bar E is in the position shown in fig. 1, it is still prevented from slipping out at either side from its place in the recess in the bar D. At *c* the bar D is made thinner and the bar E wider than at other points, so as to permit a person to readily press the bar E upward with the thumb and finger, or otherwise, to unlock the support and permit the leaf to be turned down, as indicated by the red lines in fig. 1. Should the leaf become warped, or should it sag down from the desired horizontal position, the bar D may be adjusted so as to correct such difficulty, by moving it to make the required adaptation, the slots *d* being designed to admit of such adjustment. Instead of having a link, A, enclosing a bar, D, a bar may be used instead of a link, moving in a slot in the bar D, having some suitable provision to retain such bar in the slot, as the mechanical operation would be the same in either case.

Having described the nature, construction, and operation of my invention, I will now proceed to specify what I claim and desire to secure by Letters Patent.

1. I claim the combination of a link, A, a recessed bar, D, provided with a spur, *f*, and a movable stop-bar, E, arranged and operating substantially as and for the purposes herein set forth.
2. I claim the combination of the bar D, or its equivalent, provided with the spur *f* and the movable bar E, provided with the prong or fork *g g*, arranged in the manner and for the purposes described.
3. I claim the recess *l* in the bar D, and the projection *m* on the bar E, arranged substantially as specified, to prevent the longitudinal displacement of the bar E; as described and shown.
4. I claim providing the bar D with slots *d d*, to admit of the adjustment thereof, as and for the purposes specified.

DANIEL BULL.
